UNITED STATES PATENT OFFICE.

JOHN A. POTTER, OF LOS ANGELES, CALIFORNIA.

APPARATUS FOR PRODUCING WROUGHT IRON OR STEEL DIRECT FROM ORE.

No. 874,537.

Specification of Letters Patent.

Patented Dec. 24, 1907.

Application filed January 7, 1907. Serial No. 351,237.

To all whom it may concern:

Be it known that I, JOHN A. POTTER, a citizen of the United States, residing at Los Angeles, in the county of Los Angeles and 5 State of California, have invented new and useful Improvements in Apparatus for Producing Wrought Iron or Steel Direct from Ore, of which the following is a specification.

The object of the present invention is to 10 provide an apparatus for producing wrought iron or steel direct from iron ore; also for smelting ores by means of gaseous fuel, and more particularly by the use of crude oil. The invention can be employed upon ores 15 containing other metals than iron, such as copper, silver, gold, manganese, chromium, or other ores, and combinations of ores, metals, etc.

In the accompanying drawings, Figure 1 20 is a vertical longitudinal section of my improved apparatus; Fig. 2 is a horizontal section, partly in plan view; Fig. 3 is a vertical transverse section on the line 3—3 of Fig. 2 on a somewhat larger scale; Fig. 4 is a 25 similar section on the line 4—4 of Fig. 2; Fig. 5 is a horizontal section of a modified form of the apparatus; Fig. 6 is a transverse vertical section on the line 6—6 of Fig. 5; Fig. 7 is a longitudinal vertical section on 30 the line 7—7 of Fig. 5.

Referring to the drawings, 1 indicates a furnace, formed with a bed or hearth 2 of magnesite or other suitable material. Into this furnace is fed by an inclined chute or 35 former 3, the pulverized ore 4. This ore may be mixed with suitable fluxes and reducing material, such as pulverized limestone, fluorspar, asphaltum, slack coal, peat, vegetable matter, organic refuse or other 40 hydro-carbonaceous, or carbonaceous materials, such as are capable of generating a hydrocarbonaceous or carbonaceous reducing gas to consume the oxygen in the ores, and protect the freed particles of metals 45 from oxidation while they are being melted and are also adapted to form a binder to hold the ores intact while protruding into the reducing and melting zones of the furnace. The mixture is fed by any suitable means into a 50 hopper 5, discharging into the former 3, and is slowly advanced along said former by means of a ram 6 actuated by an eccentric 7 on a shaft 8. By this means the front or advancing portion of the body of the mixture slowly

passes out of the former 4, and on to the inclined bed 2 of the furnace, and its face is thus exposed to the melting heat obtained from the combustion of fuel in the furnace melting chamber.

The fuel used to obtain the melting heat 60 is preferably fluid, and especially a hot combustible gas being preferably obtained by means of a specially constructed still. Around the steel stack 9 which carries off the products of combustion, is a steel casing 65 10, spaced therefrom to form an annular chamber 11. Crude oil, supplied to this chamber 11 by means of a pipe 12, is distilled by the heat of the gases passing up the stack, the asphaltum settling to the bottom 70 of the still, the heavy oils resting above the asphaltum, while the medium and light oils are converted into gases. The liquid residues can be tapped off from time to time by pipes 13. As a modification, additional heat 75 may be provided, if necessary, by means of a burner 14 passing into the stack through a door 40 as shown in Fig. 4.

The gas distilled by the heat of the gases passing up the stack passes by a pipe 15 to 80 one of two branches 16, leading to opposite sides of the furnace, a valve 17 being provided to change the flow of the gas from one of said branches to the other. Each branch terminates in front of the port 18 of a conduit 85 19, which conduits are used alternately as air conduits and as passages for the waste gases. Said conduits lead to the stack 9, dampers 20 being adapted to be interposed between said passages and the stack, and air valve 21 being 90 also provided to admit the air for combustion. The valve 21 and damper 20 on each side of the stack are connected by a chain 22 passing over a pulley 23, so that when the damper is open the valve is closed, and conversely. 95

Open work refractory material 24 is arranged in each conduit 19, so that said conduits can act as regenerators.

In order to insure the deoxidation reduction of the ore, and protect the metal from 100 oxidation, there are provided perforated pipes 3 extending along the bottom of the former and discharging into the ore mixture at various points adjacent to the lower side of the heating and fusing end of the ore mixture as 105 it is entering the melting zones of the furnace. Said pipes are connected with a transverse pipe 36 which again is connected preferably

by the pipe 33 with the still 11, with a source of supply of hot combustible gas under pressure.

On the opposite side of the furnace to the former is arranged the discharge spout 27 adapted to discharge the molten metal into the ladle 28 suspended in the pit 29.

A relief pipe 30, having therein a safety valve 31, is connected with the oil still, to permit the escape of gas when the pressure becomes excessive.

The following is the mode of operation of the apparatus. After there has been generated in the stack, by any suitable means, heat sufficient to distil the crude oil, the gas distilled therefrom is conveyed by the pipe 15 and one of the branch pipes 16 to one side of the furnace, and is there burned by means of hot air passed through the regenerative channel 19 on the same side, the valve 21 at that side being open and the damper 20 closed. At the same time the charge of the mixture of ore and flux and reducers is fed along the former until the face of the charge is exposed to the melting action of the flames arising from the combustion of the fuel, which flames pass over the bed of the furnace to the other side thereof, the waste gases passing out of the furnace by the mouth 18 and conduit 19 on that side, and thus to the stack 9, the damper 20 on that side being open, also hot combustible gas is forced through the perforations 26 in the pipe 25, and then through the heating and fusing body of the mixture of ore and flux in the former, and melting zones of the furnace reducing the ore and protecting from oxidation the pure metal thus obtained. This effect is likewise produced by the gases distilled from the hydrocarbonaceous material mixed with the ore. These gases, being continuously distilled from the heating and melting briquet, or body of the mixture of ore and flux or reducer, and having their only escape through the heating and fusing end and face of said briquet, at all times protect from oxidation the fibers or particles of iron or other metal that have been produced, thus enabling said particles to flow together as they emerge from the face of the briquet and drop into the liquid bath of metal contained in the furnace hearth beneath. From said hearth the metal and slags are tapped into the ladle at regular intervals.

It will be observed that in the use of this apparatus the melting heat of the furnace chamber penetrates into the advancing briquet a sufficient distance back from its fusing face to distil the gases from the hydrocarbonaceous material at such a point as to produce the best effect in the gradual consumption of the oxygen of the ore and the complete protection of the metal formed and melting on the end of the fusing briquet.

An important advantage attendant upon

the use of this apparatus is that thereby steel or wrought iron can be manufactured direct from the iron ore. By the reduction of the ore by means of hydrocarbonaceous gases and heat, the metal is extracted from the oxid substantially pure, as in the form of wrought iron, the metal liquefying and running into the hearth as the temperature is raised, and since substantially no carbon is absorbed thereby, the resulting product is wrought iron or soft steel.

I find by the use of this apparatus other ores than iron ores can be worked, such as those of copper, silver, gold, manganese, chromium or other combinations of ores; also mattes can be formed of copper, lead, silver, gold, or other metals with sulfur and iron; or any of these ores can be mixed with hydrocarbonaceous materials and fluxes, or with fluxes only, adding or allowing the sulfur that may be in the ore to form the reducing medium without binding, and permitting the front end of the body of the ore to find its natural slope, as the metal or mattes reduced therefrom melts and flows down into the liquid bath on the hearth.

When not using solid reducing materials the use of the pipes 35 is particularly advantageous, as through them the gas can freely permeate up and through the heated material in the former or furnace chamber and effect the consumption of the oxygen and the reducing of the metal and likewise protect the latter from oxidation while flowing into the liquid bath.

It may be added that steel and iron scraps, such as borings, turnings, punchings, and the like, can be mixed with the ores and carbonaceous material and fed into the hopper and former, and in this way carried into the furnace and smelted together with the ores, thereby assisting in reducing and gathering together the metals reduced from the ores, and carrying the same into the liquid bath. The percentage of scrap metals to be mixed with the ores may vary considerably and in some cases it may be desirable to smelt metal or scrap alone in this manner.

In the modification shown in Figs. 5, 6, and 7, there are provided two ore feeding devices, each comprising a hopper 5, a former 4, a ram 6, an eccentric 7 and a shaft 9. The formers are located on opposite sides of the furnace, so that the flames, in passing across the furnace, are utilized on both sides to melt briquets.

The air conduits rise below the floor to the level of the furnace instead of opposite thereto, and the pouring spout is located at the end of the furnace instead of at the side. There are shown, at this modification, pipes 25, which extend transversely through the bed of the furnace at its top, each adjacent to the lower lip of the mouth of a former. Each pipe 25 is formed with upward opening

perforations 26, and is connected with the pipe 15 containing hot combustible gases derived from the still.

I claim:—

- 5 1. In a smelting apparatus, the combination of a furnace, means for feeding ore thereto, a stack connected with the furnace, a still, heated by the stack, for distilling crude oil, a pipe for supplying the crude oil 10 to the still, a pipe for drawing off the liquid residues, and a pipe leading from the still to the furnace to conduct thereto the gas so distilled, substantially as described.
- 15 2. In a smelting apparatus, the combination of a furnace, means for feeding ore thereto, a still for distilling hydrocarbonaceous material, means for utilizing the residue heat of the furnace to heat said still, air conduits, connected with opposite sides of the furnace, 20 a stack, and means for selectively connecting the conduits with the stack to serve as flues, connections between the upper portion of the still and the opposite sides of the furnace, and means for selectively controlling the 25 flow of the gas in said branches, substantially as described.
3. In a smelting apparatus, the combination of a furnace, means for charging ore into said furnace, means for highly heating the

front surface of the ore body, and means for 30 passing combustible gas through the body of ore in the direction towards the furnace at a point behind, but adjacent to, said front surface, substantially as described.

4. In a smelting apparatus, the combination of a furnace, means for charging ore into 35 said furnace, means for highly heating the front surface of the ore body, and means for passing a reducing gas into the ore body, and through its front surface into the furnace, 40 substantially as described.

5. In a smelting apparatus, the combination of a furnace, means for supplying, to 45 said furnace, fuel and air for the combustion of said fuel means for charging ore into said furnace, means for highly heating the front surface of the ore body, and means for preventing escape, except through said front surface into the furnace, of reducing gas in contact with said ore, substantially as de- 50 scribed.

In testimony whereof I have hereunto set my hand in the presence of two subscribing witnesses.

JOHN A. POTTER.
